UNITED STATES PATENT OFFICE.

WILL D. ISEMAN, OF DETROIT, MICHIGAN.

EGG-CANDLER.

1,351,757.

Specification of Letters Patent. Patented Sept. 7, 1920.

Application filed October 31, 1919. Serial No. 334,722.

To all whom it may concern:

Be it known that I, WILL D. ISEMAN, a citizen of the United States, residing at Detroit, in the county of Wayne and State of Michigan, have invented a new and useful Egg-Candler, of which the following is a specification.

The device forming the subject matter of this application is adapted to be employed for examining eggs, and one object of the invention is to supply a structure of the kind above mentioned, in which a relatively large number of eggs may be candled at once.

Another object of the invention is to provide novel means for constructing the base portion of the candler, so as to prevent a buckling or distortion of the reflector.

A further object of the invention is to provide a candler in which the top may be made at trifling expense, the top being so constructed that a full view of all of the eggs to be candled may be obtained.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in front elevation, a device constructed in accordance with the invention, parts being broken away; Fig. 2 is a section on the line 2—2 of Fig. 1; and Fig. 3 is a section on the line 3—3 of Fig. 2.

The device forming the subject matter of this application includes a box-like base, denoted generally by the numeral 1, and including a frame 2 within which a bottom 3 is held. Disposed below the bottom 3 is a false bottom 4, preferably made of metal, the bottom 4 having an upstanding flange bound between the margin of the bottom 3 and the frame 2. Located within the frame 2 and supported on the bottom 3 is a box-like reflector 6, which, preferably, is made of metal. The relatively thick bottom 3 forms a strong support for the reflector 6 and prevents the distortion thereof. The false bot-

tom 4 protects the bottom 3 from moisture, and the bottom 3, therefore, will not warp. The construction as thus far proceeded with, results in the production of a candler includ- 60 ing a reflector which is so supported and re-inforced that the reflecting surface will remain unaltered, the efficiency of the device being thereby promoted. The reflector 6 may be secured to the frame 2 by means of 65 attaching elements 7.

Sockets 8 are carried by the upstanding wall of the box-like reflector 6, and are adapted to receive electric lamps 9 located in a circuit 10 including a push button 11 and 70 a socket 12, the socket 12 being adapted to receive a plug 14, connecting the lamp circuit 10 with the circuit 15 whereby current is supplied. The lamp circuit 10 is normally open, but may be closed momentarily, at 75 any time, by means of the push button 11 so as to cause the lamps 9 to furnish the necessary illumination. Since the lamp circuit 10 normally is open, there is a minimum waste of current in operation. 80

The frame 2 is cut away at its upper edge to form a shoulder 28, on which rests a platform 29, made of any suitable material, such as tin, the platform having any desired number of openings 30 wherein the eggs to 85 be candled are seated. The platform is supplied with a relatively large number of openings, so that many eggs may be candled at once, if desired.

The candler includes a top, denoted by 90 the numeral 16, the top comprising a frame 17 united by hinges 18 with the frame portion 2 of the box-like frame 1. The lower end of a casing is disposed within the frame 17, and this casing is a composite structure. 95 The casing includes a straight upright front wall 19 having rearwardly extended flanges 20. The casing comprises, further, a forwardly inclined back 21 having sides 22 received between the flanges 20 of the front 100 wall 19, the sides 19 of the back 21 and the flanges 20 of the front wall 19 being united by securing members of any desired construction. The lower end of the casing, constructed as above set forth, extends within 105 the frame 17, and is fastened thereto by securing elements 24. The upper end of the casing is smaller than the lower end thereof, since the back 21 slants forwardly toward the front wall 19, and, seated upon 110 the upper end of the casing, is an eye plate 25 having peep holes 26, the eye plate in-

cluding a flange 27 extended downwardly within the upper end of the casing and secured thereto in any desired way. The axes of the peep holes 26 are disposed at an obtuse angle to the vertical, and are located approximately parallel to the forwardly inclined back 21.

The general construction of the device is such that a plurality of eggs may be examined therein at once, the inclination of the eye plate and the slant of the back 21 making it convenient for an operator to look downwardly through the peep holes 26 at the eggs in the openings 30 of the platform 29, it being obvious that the eggs in the openings will be illuminated from beneath, when the push button 11 is operated to close the lamp circuit 10. The top 16 of the candler may be swung backwardly on the hinges 18, to permit the insertion of eggs into the openings 30, and to facilitate the removal of eggs therefrom.

Having thus described the invention, what is claimed is:

1. An egg candler comprising a base including a frame cut away adjacent its upper edge to form a shoulder, a main bottom within the frame; a false bottom located below the main bottom and having a flange

bound between the main bottom and the frame; a box-like reflector located within the frame and supported by the main bottom; a lamp within the reflector; a platform supported on the shoulder and provided with an egg receiving opening; and a top hinged to the base, the top being supplied adjacent to its upper end with a peep hole.

2. An egg candler comprising a top including a frame and a casing within the frame, the casing including a front wall having flanges, and an inclined rear wall including sides overlapped on the flanges; securing devices connecting the flanges with the sides; an eye plate mounted on the upper end of the casing and provided with a peep hole; a box-like base whereunto the frame portion of the top is hinged; a platform carried by the base and provided with an egg-receiving opening; and a lamp in the base, below the platform.

In testimony that I claim the foregoing as my own, I have hereto affixed my signature in the presence of two witnesses.

WILL D. ISEMAN.
